LANDON BATCHLER, OF LAWRENCEBURG, INDIANA.

DOUBLE-ACTING PUMP-OPERATING MECHANISM.

Application filed May 24, 1926. Serial No. 111,324.

The invention primarily has for its object to provide a simple and efficiently operable double acting pump operating mechanism by the use of which a steady uninterrupted pumping suction is created in the well casing providing for a steady unbroken flow of pumped liquid from the outlet thereof.

With the above and other objects in view that will hereinafter appear the invention further resides in the novel details of construction, combination and arrangement of parts, all of which will be first fully described, and then be particularly pointed out in the appended claims, reference being had 10 to the accompanying drawings in which:—

Figure 1 is a face view illustrating the invention mounted in operative relation upon a well casing.

Figure 2 is a central vertical cross section 20 of the parts illustrated in Figure 1.

Figures 3 and 4 are horizontal cross sections taken on the lines 3—3 and 4—4 respectively on Figure 1.

In the drawings in which like numerals of 25 reference indicate like parts in all the figures, 1 indicates a well casing of the deep well type, and 2 the base platform at the mouth of the well to which the base feet 3 of the side frame standards 4 are secured as 30 at 5.

The frame standards 4 are constructed as illustrated in Figures 1 and 2 of the drawings and are suitably spaced and braced as at 6.

The double acting pumping members 35 comprise the sucker rod 7 and the sucker sleeve 8, the said rod and sleeve bearing free telescopic relation one with the other and both being reciprocable centrally through the well cap 9.

The rod 7 extends up through the well cap 9 centrally between the side standards 4 to the uppermost ends thereof where it is secured in a bearing sleeve 10 slidable in the 45 bearing head 11 secured as at 12 to the upper ends of the said standards.

The sucker sleeve 8 has its upper ends secured as at 13 to the cross head 14 which is slide guided in the guides 15 provided by 50 the recesses formed in the front edges of the standards together with the removable face pieces 16 which define the foremost limits of the side guide recesses.

The cross head 14 is provided with a suitable gland 17 through which the sucker rod 55 7 passes.

A rocker arm 18 is pivoted as at 19 to each side standard 4, one end of each thereof passing through, and being oscillatable in, a slot provided in the respective side standards. The outer end of each rocker arm 18 is link connected as at 20 to the head 21 carried at the lower end of the bearing sleeve 10, the said links 20 passing through and working in slots provided therefor in the side 60 65 standards.

The inner ends of the rocker arms 18, which are projected through the side standards 4 to a point adjacent the sucker rod 7, are link connected as at 22 to the cross head 70 14, the said links 22 lying adjacent and substantially parallel to the said sucker rod.

A cross actuator shaft 23 is mounted as at 24 on the standards 4 and is provided with a suitable pulley 25 to which rotation may 75 be belt-transmitted from any suitable agency to impart rotation to the said shaft. The shaft 23 is also provided with a pair of small driver pinions 26, one thereof being mounted just outside each side standard 4. 80

The driver pinions 26 mesh with the large diameter driven gears 27 mounted upon opposite ends of the idler shaft 28 mounted in the side standards as indicated, each said driven gear being provided with a crank 29, 85 the purpose for which will presently appear.

The cranks 29 of the gears 27 are connected by the pitmen 30 with the trunnions 31 extended from the opposite ends of the cross 90 head 14 so that when rotation is imparted to the actuator shaft 23 and through it to the shaft 28 vertical reciprocatory motion will be imparted thereby to the cross head 14 through the pitmen 30. 95

By reason of the crank arm and link connections 18, 20 and 22 each time the cross head 14 is moved downwardly the sucker sleeve 8 will be moved downwardly and the sucker rod 7 simultaneously moved upwardly. On each upward stroke of the cross head 14 the reverse double action will occur, the sucker sleeve 8 being moved upwardly and the sucker rod 7 being simultaneously moved downwardly. 100 105

Thus each time the sucker rod 7 is being

moved upwardly to draw liquid from the well the sucker sleeve 8 will be moved downwardly toward its lowermost position so that immediately upon completion of the stroke 5 of the said sucker rod 7 the pumping stroke of the sucker sleeve will commence and a steady and continuous flow of liquid from the well is thereby assured.

I am aware that attempts have been made 10 to produce double acting pump mechanisms but the same have been more or less impractical because of complicated constructions or complete inability to accomplish their designed purpose of providing a perfect, steady 15 and continuous flow because of faulty construction.

The double acting mechanism which I have disclosed is practically operable, is simple and economical to manufacture and very compact 20 and sturdy in construction.

From the foregoing description, taken in connection with the accompanying drawings, it is thought that the novel details of construction, the manner of use and the advantages 25 of my invention will be readily apparent to those skilled in the art to which it relates.

What I claim is:

1. A double-acting pump operating mechanism comprising a frame including opposed side standards mountable at the mouth of a well casing, a sucker sleeve, a sucker rod, a vertically reciprocable cross head secured upon the upper end of the sucker 30 sleeve, guides for the cross head carried by the standards, a slide guide for the sucker rod mounted at the upper ends of the standards, means for reciprocating the cross head, and rocker arm and link connections for 35 causing the sucker rod and sucker sleeve to move simultaneously-reversely as the cross head is reciprocated.

2. A double acting pump operating mechanism comprising a frame including opposed 40 side standards mountable centrally over the mouth of a well casing, a sucker sleeve, a sucker rod telescopic in the sleeve and projecting vertically therethrough centrally between the standards, guides in the standards, 45 a cross head reciprocable in the guides, and secured on the upper end of the sucker sleeve, a guide for the vertically extended end of the sucker rod secured between the upper ends of the standards, means for reciprocating the 50 cross head, a rocker arm carried by each standard, and links connecting each rocker arm at one end with the cross head and at the other end with the sucker rod, whereby 55 when the cross head is reciprocated the sleeve and rod will be caused to move simultaneously- 60 oppositely.

3. A double acting pump operating mechanism comprising a frame including opposed side standards mountable centrally over the 65 mouth of a well casing, a sucker sleeve, a sucker rod telescopic in the sleeve and projecting vertically therethrough centrally between the standards, guides in the standards, a cross head reciprocable in the guides, and secured on the upper end of the sucker sleeve, a guide for the vertically extended end of the sucker rod secured between the upper ends of the standards, means for reciprocating the cross head, a rocker arm carried by each standard with one end projected inwardly within the confines of the standards and the other end projected outwardly.

sucker rod telescopic in the sleeve and projecting vertically therethrough centrally between the standards, guides in the standards, a cross head reciprocable in the guides and secured on the upper end of the sucker sleeve, a guide for the vertically extended end of the sucker rod secured between the upper ends of the standards, means for reciprocating the cross head, a rocker arm carried by each standard with one end projected inwardly within the lateral confines of the standards and the other end projected outwardly beyond the lateral confines of the standards, and links connecting each rocker arm at one end with the cross head and at the other end with the sucker rod, whereby when the cross head is reciprocated the sleeve and rod will be caused to move simultaneously-oppositely.

4. A double acting pump operating mechanism comprising a frame including opposed side standards mountable centrally over the mouth of a well casing, a sucker sleeve, a sucker rod telescopic in the sleeve and projecting vertically therethrough centrally between the standards, guides in the standards, a cross head reciprocable in the guides and secured on the upper end of the sucker sleeve, a guide for the vertically extended end of the sucker rod secured between the upper ends of the standards, means for reciprocating the cross head, a rocker arm carried by each standard with one end projected inwardly within the lateral confines of the standards and the other end projected outwardly beyond the lateral confines of the standards, links connecting the outwardly projected ends of the rocker arms with the sucker rod, and other links lying adjacent and substantially parallel the sucker rod and connecting the inwardly extended rocker arm ends with the cross head whereby when the cross head is reciprocated the sleeve and rod will be caused to move simultaneously-oppositely.

5. A double acting pump operating mechanism comprising a frame including opposed side standards mountable centrally over the mouth of a well casing, a sucker sleeve, a sucker rod telescopic in the sucker sleeve and projecting vertically therethrough centrally between the standards, guides in the standards, a cross head reciprocable in the guides and secured on the upper end of the sucker sleeve and having trunnions projecting from the ends thereof, a bearing sleeve secured to the upper end of the sucker rod and having a connector head, a guide for the bearing sleeve secured to the upper ends of and between the standards, rotatable crank gears, pitmen connecting the crank gears with the cross head trunnions, means for imparting rotation to the crank gears, a rocker arm carried by each standard with one end projected inwardly within the confines of the standards and the other ends projected outwardly.

beyond the confines of the standards, links connecting the outwardly projected ends of the rocker arms with the sucker rod, and other links lying adjacent and substantially parallel the sucker rod and connecting the inwardly extended rocker arm ends with the cross head whereby when the cross head is reciprocated the sleeve and rod will be caused to move simultaneously-oppositely, said standards having slotways for said arms 10 and the outwardly connected links to work in.

LANDON ^{his} X BATCHLER.
